UNITED STATES PATENT OFFICE.

WILLIAM A. WOOD, OF YOUNGSTOWN, OHIO, ASSIGNOR TO FRANK WOOD,
OF ALBANY, NEW YORK.

HARVESTER.

SPECIFICATION forming part of Letters Patent No. 251,986, dated January 3, 1882.

Application filed January 2, 1880. Renewed October 6, 1881. (Model.) Patented in England December 8, 1879.

To all whom it may concern:

Be it known that I, WILLIAM ANSON WOOD, of Youngstown, State of Ohio, mechanical engineer, have invented certain new and useful 5 Improvements on Harvesters; and I do hereby declare that the following is a full, clear, and exact description of the same.

Each one of the several parts of my invention relates to a combination of devices which 10 is hereinafter more particularly described and set forth, the object of my invention being to better regulate the distance of the front edge of the platform from the surface of the ground, set the upper surface of the platform at any desired incline, and effect a lowering or elevating of the same from the driver's side of the machine.

In the drawings, in which the same letters of reference indicate like parts, Figure 1 represents a side elevation of the harvester embodying the improvements of my invention. Fig. 2 represents a plan view of the same. Fig. 3 represents a plan view of the rake-head and devices operating the same. Fig. 4 represents a sectional view of the hub of the drive-wheel and locking device for locking the drive-wheel with the gear driving the rake-head. Fig. 5 is the ratchet-wheel with which the device shown in Fig. 4 operates. Fig. 6 is a view of the machine from the rear. Fig. 7 represents a view of the machine, viewed from the platform side, with platform removed. Fig. 8 represents the grain-wheel and devices for elevating and tilting the platform from said 35 grain-wheel.

In the drawings, A represents the main frame. B is the draft-pole attached to said frame.

C is the drive-wheel, loosely mounted on axle 40 a, (shown in Figs. 1, 2, 4, and 7,) which axle is supported in proper bearings from the main frame A.

D is an internal gear, cast solid with the supporting-wheel, or attached to the same, which internal gear gives motion to the spur-pinion E, Figs. 1, 2, and 7, which spur-pinion is loosely mounted on spindle b, Fig. 7, secured to the main frame A. In the head end of said spur-pinion E is provided a ratchet-wheel. Loosely 45 mounted on the same spindle b is the bevel-gear F, Figs. 1, 2, 6, and 7, the said bevel-gear carrying a dog or pawl which operates with

the ratchet-wheel carried by the spur-pinion E. When thus arranged, the drive-wheel, when revolved forward, will give motion to the spur-pinion E, which spur-pinion will, through the medium of the ratchet and pawl, give motion to the bevel-gear F; but when the said drive-wheel is revolved in an opposite direction the said bevel-gear will remain idle. 55

c is the crank-shaft box, made solid with the frame A, or attached to the same, which crank-shaft box carries the crank-shaft d. To the upper and rear end of the said crank-shaft is secured the bevel-pinion e, which bevel-pinion 60 receives motion from the gear F. To the lower and forward end of said crank-shaft is secured the balance-wheel f, which carries the pitman-connection or crank for operating pitman g, to transmit motion to the sickle or knife bar h of 70 the machine.

Loosely secured on axle a of the supporting-wheel C is the sprocket-wheel G, which communicates motion to the rake-head through the medium of the endless-chain i and sprocket-wheel G, as shown in Figs. 1, 2, and 7. One of the spokes j of the supporting-wheel C is made with a sleeve, k, running transversely with said spoke, as shown in Figs. 2 and 4. Through this sleeve works a shaft, l. To the 80 outer end of said shaft is secured a handle, m, and to the opposite end is secured the cam n. 75

Pivoted to ears made with the hub of the supporting-wheel is the dog o, which runs back to the sprocket-wheel G, and engages with the 85 teeth of an internal ratchet-wheel, p, made in said sprocket-wheel G, as shown in Figs. 2 and 4. A spring placed between dog o and the hub of the supporting-wheel throws said dog up, so that its end will engage with the ratchet-wheel 90 in the sprocket-wheel G. When the handle m is turned in a direction transverse to the direction of spoke j the dog o will engage with the ratchet-wheel of the sprocket-wheel G, and the said sprocket-wheel will be revolved by the 95 drive-wheel, when in motion, in a forward direction. When the handle m is turned back and in a direction parallel with the spoke j the cam n on shaft l will be turned down on the dog o, to depress the same and throw its free 100 end out of engagement with the ratchet p of the sprocket-wheel G, when said sprocket-wheel will remain idle.

Arranged parallel with the side of the main

frame toward the platform H is the tilting frame I, Figs. 1, 2, 6, and 7, which tilting frame carries the platform H and its sickle-bar and guards and the rake. The forward end of the 5 said tilting frame is supported by the eccentric J and its rearward end by the tilting shaft K. The eccentric J is fixed securely to shaft a, on which the drive-wheel revolves, and works in the flanged way x x, made solid with said tilting frame, as shown in Figs. 1, 2, 6, and 7. Firmly secured to the opposite end of shaft a, and directly opposite the platform M of the 10 driver's seat L, is the worm-gear wheel N. Working in said worm-gear wheel is the screw 15 P, which screw is provided with a crank, Q, extending up vertically to near the plane of the driver's seat. When the crank Q is revolved in one direction the screw P will also be revolved, and will operate with the worm-gear 20 wheel N and revolve it forward, and carry with it the shaft a of the drive-wheel, and also the eccentric J, attached to the opposite end of said shaft. When the said eccentric is thus 25 moved its throw from the shaft will be downward, and in such a manner as to cause the eccentric to revolve in the flanged ways x x of the tilting frame and depress the forward end of the same, and carry with it the platform H, with its sickle-bar, and also the rake-head. A 30 reverse movement of the crank q will revolve the screw P in an opposite direction, and so operate the worm-gear as to carry the eccentric J upward, so as to carry the tilting frame up, and thereby elevate the platform and rake 35 to a higher plane.

The tilting shaft K, for elevating or depressing the rearward portion of the tilting frame I, extends across the rear end of the main frame A, and is supported in bearings in the same, 40 as shown in Figs. 1, 2, and 6. The end of said tilting shaft next to the tilting frame I is provided with a crank, q, the end of which crank works in slot r, made in the rear end of said tilting frame, as shown in Figs. 2, 6, and 7. Secured to the opposite end of the said tilting 45 shaft K is the hand-lever R, which carries the finger s and elastic dog s', as shown in Figs. 2 and 7. The dog s' works in a segmental tooth-rack, t, and operates to hold the tilting shaft 50 K in any position it may be set to. When the hand-lever R is thrown forward the tilting shaft will be moved in a corresponding direction, and the crank q of said tilting shaft will be thrown downward at its free end, and carry 55 with it the rear end of the tilting frame I. A reverse movement of the hand-lever R will move the crank q of the tilting shaft in an opposite direction and elevate the rear end of the tilting frame. When the eccentric J has 60 been operated to carry its greatest throw downward the tilting frame will be depressed, and will carry with it the guards and sickle-bar attached to the front of platform H, and when in this condition it is desired to give to the 65 platform but a slight inclination, the hand-lever R is to be moved forward, when the crank of the tilting shaft will be thrown downward,

and will carry with it the rear end of the tilting frame I, and consequently depress the rear end of the platform H, and thereby cause the 70 platform to have its upper surface about on a plane parallel with the surface of the ground, or to a greater or less angle with the same, as may be selected, accordingly as the rear end of the tilting frame is moved by the tilting 75 shaft.

Secured to the machine from the main shaft a of the drive-wheel and the projecting end of spindle b (shown in Figs. 2 and 7) is the depressing-way T. 80

Pivoted to the platform H, at its lower side, is the shaft u, held in proper bearings secured to said platform, as shown in Fig. 6. The end of said shaft toward the tilting frame is provided with a right-angular piece forming lever 85 u', which lever is provided with a grooved head, v, which receives the lower side edge of the depressing-way T, as shown in Figs. 2, 6, and 7.

Made with the end of shaft u, next to the 90 grain-wheel U, is the crank v', Figs. 2 and 8, which crank works in the grain-wheel arm or lever V, hinged to the platform H at a point rearward of said grain-wheel, as shown in Fig. 8. The spindle of said grain-wheel U is secured to said lever V. The said lever is held in place by the guide w, secured to said platform and clasping the said lever at a point forward of the pivot by which it is connected to the platform. When the rear end of the tilting frame I is depressed the platform H, in its rearward portion, will also be depressed, while the grooved head v of lever u' of shaft u will ride on the lower side of the depressing-way T, and the crank v' of shaft u will be thrown 105 upward, and thereby carry upward the spindle of the grain-wheel U, when the rear end of the platform will be depressed on the grain-wheel side, correspondingly with the rear end of the same at the tilting-frame side, so that 110 both sides of the platform will be on the same plane.

A draw-rod, b', connects the pole B to the platform H by means of stud a', secured to the pole, and stud a'', secured to said platform, as 115 shown in Figs. 1 and 2. A stiffening-rod, c', having one end connected to stud a'' on the platform and its opposite end to the tilting frame I, stiffens the connection of said platform with said tilting frame. 120

Secured to the forward portion of the tilting frame I, Figs. 6 and 7, is a bracket, A', which bracket supports shaft B', supported in suitable bearings from said bracket in a position nearly vertical to the plane of platform H. The 125 said shaft, which is free to revolve, is made to turn in its bearings by the bevel-gear C', actuated by the bevel-pinion D', secured to the shaft carrying the sprocket-wheel G, and supported from the tilting frame by suitable bearings.

Secured to the upper end of the vertical shaft B' is the head-piece E', having ears e' e', to which the ends of the rake-arms F' F' are pivoted. The said rake-arms carry the rake H' H'. 130

Arranged in a fixed manner on a plane below the head-piece E' is the cam-track J'. The said cam-track has its way so formed that portion 1 of said track, toward the drive-wheel, will be nearly horizontal and on a higher plane than its opposite side vertical portion, 2, toward the platform side, while the portion 3 of said track will have a gradual descent from the horizontal portion 1 toward and to the vertical portion 2, and the rearward portion, 4, will have a sudden rise from the vertical portion 2 to the horizontal portion 1, as shown in Figs. 2, 3, and 6. The rake-arms F' are hinged to the head-piece E' by means of the metallic arms F². Each metallic arm is provided with a roller, z, which rollers, when the rake-head E' is revolved, will revolve on the faces of the several portions, 1, 3, 2, and 4, of the cam-track and cause the rake-arms and their rakes to be successively elevated and lowered. The said rollers are arranged nearly at right angles with the metallic arms F², so that when they are brought to revolve on the horizontal portion 1 of the cam-track the rake-arms will be elevated, as in Fig. 6, and when they are carried forward and descend on the forward portion, 3, of the track the said rake-arms will be gradually depressed, so as to cause the rakes H' to work against the standing grain and carry it toward the platform, while when the roller of an arm passes rearward and against the vertical portion 2 of the track the rake will sweep the platform clear of the accumulated cut grain thereon and throw it rearward of the platform. When the said roller passes entirely to the rear portion, 4, of the cam-track the sudden incline of said portion 4 of the track will cause the rake-arm to be elevated the same as when first started.

Supported from the side of the continuous cam-track J' toward the platform H, and from the vertical side portion, 2, of the same, is the bracket K', provided on its upper side with a way, which works the sliding piece, L' Fig. 3, which sliding piece carries a section, 5, of the beater-track. The inner face side, m', of said sliding section 5 of beater-track is so formed that when the roller z of a rake arm passes between the said face m' and the vertical portion 2 of the continuous cam-track J' the rake-arm will be locked down from all liability of jumping upward. The outer side face, n', of said sliding section 5 is so formed as to run from a vertical line of surface to one which is oblique or inclined, so that when the said sliding section 5 is moved back against the vertical portion 2 of the cam-track J', as indicated by dotted lines in Fig. 3, the roller z of a rake-arm will move against said face n' of said sliding section 5 and cause the rake-arm to be gradually elevated.

Cast solid with bracket K' is a fixed section, 6, of the beater-track, the face of which is so formed that the roller z of a rake-arm revolving against the same will force the rake-arm upward to a higher elevation than when mov-

ing against the face side n' of the sliding section 5.

Pivoted from ears p', Fig. 3, made with the base portion of the continuous cam-track J', is the switch-track 7, which forms a section of the beater-track and leads the roller z of a rake-arm from the sliding section 5 and fixed section 6 to the main continuous cam-track J', so as to raise the rake-arm to its highest elevation. When the sliding section 5 of the beater-track is moved off from the vertical section 2 of the continuous cam-track J', as shown by full lines in Fig. 3, the rollers z of the rake-arms will move successively against the faces of the portions 1, 3, 2, and 4 of said cam-track and cause the rakes (as they are continuously revolved) to alternately rise and descend against the standing grain to carry it back toward the platform, and then to descend to the platform and sweep the entire surface of the same to bunch the cut grain fallen thereon and deliver the same on the surface of the ground rearward of the machine.

When the sliding section 5 of the beater-track is moved against the vertical section 2 of the continuous cam-track J', so as to cause the roller z of the rake-arms to move against the outer surface, n', of the said sliding track-section 5, the rakes, as they are revolved by the head-piece E', will be successively elevated and depressed for operation as beaters to carry the standing grain toward the platform, but not for operation as rakes to sweep the platform clear of the fallen grain.

To effect an automatic movement of the sliding section 5 of the beater-track toward and from the main and continuous cam-track J', for causing the rakes to operate alternately as beaters and rakes, I provide the following devices and mechanism:

Made with the lower side of the head-piece E' (shown in Fig. 3) are one or more downwardly-projecting pieces, q', which pieces revolve with said head-piece continuously. Secured to the upper end of a vertical pivot working in a bearing made solid with the cam-track J' is the lever-arm r'. (Shown in the same figure.) Secured to the lower end of the same vertical pivot is another lever, x', which lever is connected by connecting-rod x² to another lever, y, (shown by dotted lines in Fig. 3,) arranged below the sliding piece L', and secured to the lower end of the vertical pivot z' of a tripping-lever, c'. The lever y is yoked to a sliding latch, e², (shown by dotted lines in Fig. 3,) which sliding latch works in the lower side of the sliding piece L', and is provided with a holding-lip on its head end toward the continuous cam-track, and is adapted to engage with the head end of said sliding piece L'. The vertical pivot to which the levers or arms r' and x' are secured is made with a greater length than the length of the bearing in which said vertical pivot works, and is made elastic by a spring, (not shown,) which spring so operates

with the said pivot and its attached lever-arms as to hold the lever r' up to a plane on a horizontal line above the lower ends of the downwardly-projecting pieces q', q' , carried by the head-piece E' . A spring, s^2 , Fig. 6, is provided on the lower side of the sliding piece L' , and connecting from the head end of the same to the outer end of the bracket K' , for the purpose of drawing the sliding section 5 of the beater-track to the vertical section 2 of the continuous cam-track J' .

Supported from the bracket supporting the rake head shaft B' is the bracket-arm d^2 , which carries a crank-shaft, f^2 , Figs. 2, 3, and 6, supported in suitable bearings. Made with the end of said crank-shaft toward the rake-head is the arm g^2 , which rests on the heel of lever x' . (Shown by dotted lines in Fig. 3 and full lines in Fig. 6.) Pivoted to the outer arm crank end of shaft f^2 is the draw-rod h^2 , which connects in a pivoted manner to the short end of the foot-lever m^2 , having for its fulcrum the outer end of the shaft a of the supporting-wheel C , as shown in Figs. 1, 2, and 6.

The manner in which the several parts of this mechanism operates is as follows: When the head-piece E' is revolved continuously by the mechanism provided the downwardly-projecting pieces q' on said head-piece will strike on the inner side edge of the lever-arm r' , and so press on it as to cause it to turn outward, when the lever x' below, secured to the same pivot, will also be moved outward and draw, by the connecting-bar x^2 , the lever y in the same direction. This movement of the lever y will be in a direction toward the continuous cam-track J' , and being secured to the vertical pivot z' of the tripping-lever c^2 will cause the free end of the said tripping-lever c^2 to be moved toward the said cam-track. The lever y , when moved toward the cam-track, will, by reason of its being yoked to the sliding latch e^2 , carry said sliding latch forward and throw its catching head end in engagement with the lower side of the head end of the sliding piece L' , which carries section 5 of the beater-track, while at the same time the said sliding section 5 will be carried by spring s^2 up to the vertical section 2 of the continuous cam-track J' . When the several parts are in this position the tripping-lever will be partially over the groove-track of the rollers z of the rake-arms, so that when the head-piece E' is made to continue its revolution, and the projecting piece q' has been carried past the lever r' , the latch-piece e^2 will be set for operating the sliding piece L' to move it back and carry the sliding section 5 of the beater-track off from the main cam-track J' , to permit the roller z of the first approaching rake-arm to pass between the vertical section 2 of the cam-track and the face m' of said sliding section 5. This movement of the sliding piece L' and its section 5 of the beater-track is effected by means of the roller z of the first approaching rake-arm, which roller will, on its

forward movement, press against the tripping lever or arm c^2 and force it to move outward, and by means of its vertical pivot z' , to which it and the lever y beneath are secured, the said lever y will also be moved outward, and will carry with it the latch-piece e^2 , engaging with the sliding piece L' , and draw said sliding piece and section 5 of the beater-track with it from the cam-track, when the roller z of the said approaching rake-arm will pass between the face m' of the said section 5 and the vertical face-section 2 of the cam-track J' , and the rake attached to the said rake-arm will be depressed, and will be made to sweep over the entire surface of the platform and clear it of the cut grain fallen thereon. As soon as the roller z of the said rake-arm has passed out between the said two sections 5 and 2 another projection, q' , made with the head-piece E' , will operate with the lever r' to reset the several parts for another operation.

When four rake-arms with rakes are employed I use two projections, q' , one situated opposite to the other, as shown in Fig. 3, and thereby secure an alternate rake and beater movement of the rakes, which are adapted to be thus used alternately in good or heavy grain. When the grain is light in its straw, and it is desired to have the machine travel a greater distance before discharging the cut grain from the platform in bunches, the driver will with his foot press on the foot-lever m^2 , when said lever will operate the crank-shaft f^2 and cause the arm g^2 to press on the heel of lever x' , and thereby carry said lever, together with the lever r' , downward, so that the upper surface side of said lever r' will be carried below the plane of the lower ends of the projections q', q' , carried by the head-piece E' , when the said projection will pass free from contact with lever r' , when said lever will be unaffected, and consequently the sliding section 5 of the beater-track will be held up to the vertical face-section 2 of the main track by the force of the spring s^2 in Fig. 6, and not by the sliding latch-piece e^2 , as before described. In this condition of parts the rakes will be revolved only as beaters, and will not operate as rakes for sweeping the platform clear of grain, as the rollers z will revolve against the face n' of the sliding section 5 of the beater-track, and not between said section and the vertical face-section 2 of the main cam-track; but when the driver removes the pressure of his foot from lever m^2 the projections q', q' will operate against the lever r' , which will be carried upward by the spring before referred to, to give movement to the several parts operating to set the sliding latch-piece e^2 and tripping-arm c^2 , when the rake-arms will revolve and be made to operate the rakes alternately as beaters and rakes.

What I claim, and desire to secure by Letters Patent, is—

1. In combination with the main frame A and with the tilting frame which carries the

platform and rakes, the eccentric J, adapted to operate directly upon the said tilting frame, said eccentric being fixed on the shaft a , on one side of the main supporting-wheel, and having a lever fixed to the opposite end of said shaft a , in described relation to the driver's seat, as set forth.

2. In a harvester, the combination, with the main frame A and tilting frame I, carrying platform H, and capable of being variously elevated or lowered in relation to said main frame, of the tilting shaft K, operating with the rearward end of said tilting frame, whereby said tilting frame may be variously inclined, substantially as and for the purpose set forth.

3. In a harvester, the combination of a main frame supporting the platform, rakes, and mechanism for revolving said rakes, a tilting frame, and devices for elevating and lowering said tilting frame, both in front and rear, from the driver's-seat side, said devices also supporting the tilting frame.

4. The combination of the main frame, supporting platform and rakes, and mechanism for revolving said rakes, with eccentric J on shaft a , and operating mechanism within reach of the driver, and with the shaft K and connections, whereby the frame may be tilted from front or rear by the driver, as set forth.

5. The combination, with the main frame A and tilting frame I, of the tilting shaft K, provided with crank q , operating with the rear end of said tilting frame, segmental toothed rack t , and lever R, carrying dog s' , substantially as and for the purpose set forth. 35

6. The depressing-way T, secured to the main frame, and shaft u , supported from platform H, and provided with the lever-arm u' , acting against said depressing-way, and with crank v , operating with the pivoted lever V, carrying grain-wheel U, whereby the grain-wheel side of said platform will be made to assume a position uniformly the same with the opposite side, in the manner and for the purpose set forth. 40

7. In combination with the supporting-wheel C, the sleeve k , shaft l , provided at one end with cam n and at the other end with handle-lever m , projecting from the driver's side of said drive-wheel, dog o , and internal ratchet-wheel p , made with the sprocket-wheel driving the revolving rakes, substantially as and for the purpose set forth. 45

WM. ANSON WOOD.
